UNITED STATES PATENT OFFICE.

FRED T. WEAVER, OF FRACKVILLE, PENNSYLVANIA.

CUT-OFF.

1,294,003.

Specification of Letters Patent.

Patented Feb. 11, 1919.

Application filed April 4, 1918. Serial No. 226,774.

To all whom it may concern:

Be it known that I, FRED T. WEAVER, a citizen of the United States, residing at Frackville, in the county of Schuylkill and State of Pennsylvania, have invented certain new and useful Improvements in Cut-Offs, of which the following is a specification, reference being had to the accompanying drawings.

10 This invention relates to certain improvements in automatic cut-offs and has relation more particularly to a device of this general character especially designed and adapted for use in connection with a gas line and it 15 is an object of the invention to provide a novel and improved cut-off of this type which is normally maintained in open position under the influence of the pressure of the gas passing through the line and which 20 automatically assumes a closed position upon dropping of the gas pressure.

It is also an object of the invention to provide a novel and improved automatic cut-off which is manually moved into open position and which is maintained in such position through the medium of the pressure of the gas flowing through the line.

Another object of the invention is to provide a novel and improved device of this 30 general character including a valve chamber interposed in the pipe line and which chamber is provided with a port in communication with the atmosphere together with a swinging cut-off which automatically assumes 35 a closed position upon a material decrease in the pressure of the gas flowing through the line and which cut-off shuts off the flow of the gas through the port when the cut-off is in open position together with an automatically 40 operating valve for closing the port when the cut-off is in closed position.

The invention consists in the details of construction and in the combination and arrangement of the several parts of my improved cut-off whereby certain important advantages are attained and the device rendered simpler, less expensive and otherwise more convenient and advantageous for use, as will be hereinafter more fully set forth.

45 50 The novel features of my invention will hereinafter be definitely claimed.

In order that my invention may be the better understood, I will now proceed to describe the same with reference to the accompanying drawings, wherein:

Figure 1 is a longitudinal sectional view

illustrating an automatic cut-off constructed in accordance with an embodiment of my invention, the cut-off being shown in its raised position, said closed position of the cut-off being indicated by dotted lines;

Fig. 2 is a transverse sectional view taken through the device as disclosed in Fig. 1 with the cut-off in closed position; and

Fig. 3 is a view in top plan of the valve for closing the port in communication with the valve chamber.

As disclosed in the accompanying drawings, B denotes a boxing interposed in the pipe line L and which line leads from a suitable source of gas supply and delivers to any desired location. The section 1 of the pipe line L leading from the box extends slightly within the box and has its inner edge 2 arranged on a bevel.

75 The box B includes the removable lid or cover C held to the box in a conventional manner through the medium of the screws 3 or the like and interposed between the lid or cover C and the adjacent edge faces of the box B is a gasket 4 whereby a hermetic closure is assured with the lid or cover C in applied position.

Disposed transversely through the box B adjacent the discharging end thereof and in close proximity to the lid or cover C is a shaft 5 having one end portion extending exteriorly of the box B and provided with a ring 6 or the like whereby the shaft 5 may be manually rotated with convenience and facility.

Arranged within the box B and loosely engaged with the shaft 5 are the extremities of a yoke 7 herein disclosed as substantially U-shape in form and provided at substantially its center with an arm 8 extending in a direction away from the shaft 5 and terminating in the enlarged eye or annular member 9. The yoke 7 and the arm 8 afford a member substantially in the form of a Y.

100 V denotes a valve or cut-off formed preferably of rubber and having embedded therein a reinforcing disk 10 preferably of metal. The valve or cut-off V is circular in form and has its marginal or peripheral portion provided with the oppositely directed flanges 11 formed of thin rubber and converging in cross section whereby the valve or cut-off is substantially cup-shape at opposite sides. When the valve or cut-off V is in its 110 elevated or raised position one of the flanges 11 contacts with the lid or cover C. The lid

or cover C within the area defined by the valve or cut-off V when raised or elevated is provided with a port 12 in communication with the atmosphere which results in the formation of the necessary suction for maintaining the valve or cut-off elevated under the influence of the pressure of the gas passing through the line L as such gas will have a natural tendency to escape through the port 12. When the pressure of the gas within the line L materially decreases the valve or cut-off will automatically form and seat upon the end of the section 1 of the line L extended within the box B so that upon the pressure of the gas returning to normal, the gas can not flow from the box B. By this means it will be at once self-evident that no gas will be able to escape through the burners which may have been extinguished upon the dropping of the gas pressure.

Carried by the shaft 5 is a rock arm 14 of a length to engage the intermediate or base portion of the yoke 7 so that upon imparting the requisite rotation to the shaft 5 the valve or cut-off V may be readily returned to its normal position or in contact with the lid or cover C as illustrated in Fig. 1.

I find it of advantage to have the arm 14 normally maintained in lowered position so that the possibility of said arm offering any obstruction or hindrance to the dropping of the valve or cut-off V is avoided. For this reason I employ the spring 15 having one end portion engaged with the arm 14 and its opposite end portion contacting with the lid or cover C with the intermediate portion 16 of said spring coiled about the shaft 5. As the yoke 7 is loosely engaged with the shaft 5 it will be understood that the spring 15 may readily return the arm 14 to its normal position without affecting the normal or raised position of the valve or cut-off V.

Supported intermediate its length by the inner face of the lid or cover C is an arm 17 having one end portion provided with the pad 18 of rubber or kindred material and which pad serves to close the port 12 when the valve or cut-off V is in lowered position so that gas is prevented from escape through the port 12 after the gas pressure has been raised and before the valve or cut-off V is again elevated. The support for the arm 17 is so positioned as to permit the weight of the end portion of the arm 17 at the side of the support therefor remote from the pad 18 to automatically cause the pad 18 to assume a closed position when the valve or cut-off V is lowered. This portion of the arm 17 is also of such a length as to be engaged by the valve or cut-off V when raised so that the pad 18 will be thrown into an open position. The pad 18 and the arm 17 constitute a valve. It will also be understood that the box B affords a valve chamber.

From the foregoing description, it is

thought to be obvious that a cut-off constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a gas line, a box interposed therein, a wall of said box being provided with a port, a swinging cut-off mounted within the box and assuming a closed position upon dropping of pressure within the pipe line, means for moving the cut-off into open position, said valve when in open position being maintained by the gas pressure in contact with the wall of the box provided with the port, said cut-off when in contact with said wall preventing flow of gas through the port, and means within the box automatically operating to close the port when the cut-off is in closed position.

2. In combination with a gas line, a box interposed therein, a wall of said box being provided with a port, a swinging cut-off mounted within the box and assuming a closed position upon dropping of pressure within the pipe line, means for moving the cut-off into open position, said valve when in open position being maintained by the gas pressure in contact with the wall of the box provided with the port, said cut-off when in contact with said wall preventing flow of gas through the port, and a member automatically operating to close the port when the cut-off is in closed position.

3. In combination with a gas line, a box interposed therein, a wall of said box being provided with a port, a swinging cut-off mounted within the box and assuming a closed position upon dropping of pressure within the pipe line, means for moving the cut-off into open position, said valve when in open position being maintained by the gas pressure in contact with the wall of the box provided with the port, said cut-off when in contact with said wall preventing flow of gas through the port, and automatic means for maintaining the means for moving the cut-off into open position free of said cut-off when the cut-off is in contact with the wall of the box provided with the port.

4. In combination with a pipe line, a box interposed therein, a shaft disposed through the box and provided with operating means, a member loosely engaged with the shaft for swinging movement, a cut-off carried by the

member and preventing flow from the box when the cut-off is in closed position, and a rock arm carried by the shaft and engageable with the member for moving the cut-off into open position upon rotation of the shaft in one direction.

5. In combination with a pipe line, a box interposed therein, a shaft disposed through the box and provided with operating means, a member loosely engaged with the shaft for swinging movement, a cut-off carried by the member and preventing flow from the box when the cut-off is in closed position, a rock-arm carried by the shaft and engageable with the member for moving the cut-off into open position upon rotation of the shaft in one direction, and means for automatically moving the shaft in the opposite direction.
- 10 6. In combination with a gas line, a box interposed therein, a wall of said box being provided with a port, a swinging cut-off mounted within the box and assuming a closed position upon dropping of pressure within the pipe line, means for moving the cut-off into open position, said valve when in open position being maintained by the gas pressure in contact with the wall of the box provided with the port, said cut-off when in contact with said wall preventing flow of gas through the port, and means automatically operating to close the port when the cut-off is in closed position, said cut-off when in contact with the wall provided with the port adjusting said last named means into open position relative to the port.
- 15 7. In combination with a gas line, a box interposed therein, a wall of said box being provided with a port, a swinging cut-off mounted within the box and assuming a closed position upon dropping of pressure

within the pipe line, means for moving the cut-off into open position, said valve when in open position being maintained by the 45 gas pressure in contact with the wall of the box provided with the port, said cut-off when in contact with said wall preventing flow of gas through the port, an arm positioned within the box and supported for 50 swinging movement by the wall of the box provided with a port, an end portion of the arm closing the port when the cut-off is in closed position, said cut-off contacting with the arm when in open position to open 55 the port.

8. In combination with a gas line, a box interposed therein, a wall of said box being provided with a port, a swinging cut-off mounted within the box and assuming a 60 closed position upon dropping of pressure within the pipe line, means for moving the cut-off into open position, said valve when in open position being maintained by the gas pressure in contact with the wall of the 65 box provided with the port, said cut-off when in contact with said wall preventing flow of gas through the port, an arm positioned within the box and supported for swinging movement by the wall of the box 70 provided with a port, an end portion of the arm closing the port when the cut-off is in closed position, said cut-off contacting with the arm when in open position to open the port, said arm moving by gravity to 75 close the port.

In testimony whereof I hereunto affix my signature in the presence of two witnesses.

FRED T. WEAVER.
